UNITED STATES PATENT OFFICE.

EMILE RIMAILHO, OF PARIS, FRANCE, ASSIGNOR TO COMPAGNIE DES FORGES & ACIERIES DE LA MARINE ET D' HOMECOURT, OF PARIS, FRANCE.

TUYÈRE WITH VARIABLE OUTPUT FOR CANNON.

Application filed July 13, 1925. Serial No. 43,355.

To all whom it may concern:

Be it known that I, EMILE RIMAILHO, a citizen of the Republic of France, residing at Paris, in the Seine Department, Republic 5 of France, have invented certain new and useful Improvements in Tuyères with Variable Output for Cannon; and I do hereby declare the following to be a full, clear, and exact description of the invention, such as 10 will enable others skilled in the art to which it appertains to make and use the same.

There is known a device for regulating the discharge of gas in cannon, comprising a partition separating the bore properly so 15 called from the chamber in which the combustion of the powder is effected, said partition being pierced with an orifice or tuyère in which is engaged, in the firing position, a projection extending rearwardly of the 20 projectile in such manner as to effect a momentary closing of said tuyère when the shot is fired.

In these conditions, the movement of the 25 projectile when fired is less rapid than if the gas acted upon the whole surface of the bottom of the projectile, and on the other hand a given displacement of the projectile will cause a much smaller augmentation of 30 the space offered to the gas. The combustion of the gas may thus take place almost at a constant volume, and its pressure may attain a high value before the tuyère is disengaged.

There is thus obtained a very regular 35 combustion of the powder.

The present invention relates to improvements in the arrangement above mentioned in order to permit, in the same conditions of the regular combustion of the powder, 40 the firing at variable initial velocities below the normal initial velocity.

According to this invention, I obtain the 45 reduction in the initial velocity without diminution of the charge and without increasing the volume of the chamber, by allowing to escape to the exterior; a part of the gas resulting from the combustion of the powder, this discharge commencing only when the projectile has already assumed a 50 certain displacement, and this insures, during a sufficient time to allow the pressure to attain a high value, a combustion identical with what is produced when no discharge takes place.

Further, the arrangement is such that the 55 discharge commences before the tuyère is disengaged by the obturating projection, so that the output of the tuyère will be from the start of the flow into the cannon bore, less than what it would have been without 60 the said discharge.

For this purpose there is formed in the partition a discharge conduit having its output orifice in the wall of the tuyère, so as to be closed by the projection of the bottom of the projectile. The said conduit 65 communicates with a cock permitting to regulate the discharge of the gas.

When the said cock is closed, the discharge of gas is null, the output of the 70 tuyère is a maximum, and the projectile is fired at the maximum initial velocity. When the said cock is open, the gas may escape to the exterior as soon as the orifice of the discharge conduit is uncovered by the projection of the bottom of the projectile, i. e. 75 somewhat before the tuyère is itself disengaged.

There will evidently result a reduction in 80 the output of the said tuyère and consequently a reduction in the initial velocity.

What characterizes the present invention is not the feasibility of reducing the initial velocity by the discharge to the exterior of 85 a portion of the gas produced by the combustion of the powder, but it is the particular combination which is made between this process for the reduction of the initial velocity, and the use of a tuyère and of a projectile provided with an extension piece 90 serving to close the said tuyère. This combination offers the particular advantage of permitting to vary the initial velocity within wide limits but without change in the regularity of the combustion of the powder, 95 since the discharge orifice, covered by the extension piece of the projectile, is only uncovered after the pressure has attained a high value, as above set forth.

Another feature of the invention is the 100 use of a cock permitting the progressive regulation of the discharge, and I may thus progressively vary the initial velocity. In these conditions, the progressive variation in the firing distance which is necessary in 105 regulating the firing may be obtained either in the ordinary manner by leaving the velocity constant and by progressively vary-

ing the angle, or on the contrary by leaving the angle constant and progressively varying the speed.

Finally, I may connect the control of the cock with the control of the mechanism for the elevation, in order to progressively vary by means of a single control the firing angle as well as the initial velocity. This latter method of realization will allow of continuously covering by a single and very simple operation the entire region which is capable of being attained by the projectiles, from the greatest range obtained with the highest initial velocity and a firing angle of 45°, to the smallest range obtained with the smallest initial velocity and the smallest firing angle in the case of horizontal firing, or the largest angle in the case of vertical firing.

20 The arrangement according to the invention is not solely applicable to projectiles with studs and to a cannon whose firing charge is introduced through the breech. It may further be utilized when the projectile 25 is provided with stabilizing wings or when it carries its own firing charge. The projectile may even be of the wing type and carry its own firing charge.

30 The appended drawings show by way of example an embodiment of the invention, a modification of the form of the cock, and a modified form of construction corresponding to the use of projectiles carrying their own firing charge.

35 Fig. 1 is a lengthwise section of a cannon constructed according to the invention.

Fig. 2 is a transverse section of the cock.

Fig. 3 is a side view of the cannon mounted on its carriage to show the connection between the mechanism for the control of the plug of the cock and the mechanism for the elevation.

Fig. 4 is a partial section on the line A—A of Fig. 3.

45 Fig. 5 is a partial lengthwise section of the cannon showing by way of modification the use of a disk cock.

Fig. 6 is a horizontal view of the cock shown in Fig. 5, showing the form of the orifices in said disks.

Figs. 7 and 8 show a modified embodiment of the invention in the case in which the projectile carries its own firing charge.

Fig. 1 shows the cannon 1 which is divided into two parts by the partition 2, pierced with an orifice or tuyère in which is engaged the projection 4 secured to the bottom of the projectile 3. A conduit 5 formed in the body of the partition 2 and opening into the wall 60 of the tuyère, serves to connect this latter with a discharge tube 6 disposed along the cannon, through the medium of a cock 7 whose plug 8 is rotatable in a cylindrical body or chamber 9 so as to close or open the orifice of the tube 6.

The cock is shown in section on its axis in Fig. 2. It is obvious that the part 10 of this axis which extends to the exterior may be actuated by means of a knob, a crank or in any other manner, and that a dial concentric with the axis will allow of indicating the positions to be given to the cock plug in order to obtain the desired velocities. In the case above considered in which one fires at a constant angle and at a variable initial velocity, the dial of the cock may be graduated in firing distances. But it has also been stated above that it may be advantageous to regulate the degree of opening of the cock in proportion to the angle of aiming for elevation; a form of realization of this latter means for controlling the cock plug is shown, in Figs. 2 to 4.

This form of realization is given solely by way of example, and any other device providing for the connection between the said cock and the means for aiming for elevation while permitting the recoil of the cannon may be employed instead of the one herein described. Such devices are in current use for varying the length of the recoil in proportion to the firing angle, for apparatus in which the brake body is subject to recoil, for example.

To the shaft 10 is keyed a bevel pinion 11 which is actuated by a set of pinions contained in a casing 12 secured to the main body of the cock. The end pinion 13 is slideable on a rod 14 mounted on an arm 15 which is secured to the non-rolling part of the pivoting aggregate. In the rod 14 is a longitudinal slot in which is slideable a stud carried by the pinion 13, thus obliging this latter to rotate with the rod 14. The latter carries at the front end an actuating pinion 23 (Fig. 4) in gear arrangement with a lateral toothed portion 24 of the sector for aiming for elevation 16. The arm 16 carries at the end the elevation mechanism comprising an operating crank 17 which actuates by bevel pinions and worm gearing the outer toothed portion of the sector 16.

The values of the elevation are read upon the outer face of the sector 16 opposite a pointer 25 mounted on the arm 15. To correct the error due to an inclination of the carriage to the front or rear, the sector 16 is not fixed with reference to the small pivoting carriage 20. A mechanism analogous to the elevation mechanism, but mounted on the small carriage 20, allows of turning together as a whole the pivoting aggregate and the said sector, by acting upon the knob 21 which actuates—by bevel pinions and worm gearing—an inner toothed portion formed on the lower part of the sector 16. A spirit level 22 mounted on the sector 16 serves to check the proper inclination of the latter.

The sector 16 is graduated in such manner that the figure which is observed adjacent

the pointer 25 represents the firing distance, resulting from the firing angle and the initial velocity which corresponds to this position of the arm 15 relatively to the sector 16.

5 The transmission should obviously be effected in such manner that the closed position of the cock for which the initial velocity is the greatest, corresponds to an angle of 45°, this will afford the maximum firing distance. The rotation of the pivoting mass either way from 45° will effect more or less rapidly the opening of the cock, which should be entirely open for the minimum angle and the maximum angle allowed by 10 the carriage.

15 It is feasible to vary the conditions uniting the degree of opening of the cock to the angle of aiming for elevation, and thus to arrange matters so that the firing distance 20 shall vary according to the firing angle according to a rate which is considered the most suitable.

25 One may act for this purpose upon the ratio of transmission of the set of gearing, upon the dimensions and the original setting of the cock plug and upon the form of the adjustable orifice of the cock. One may further employ, in the gear transmission, means known per se comprising for instance a cam with suitable outline to suitably vary the ratio between the rate of rotation of the cock plug and the rate of variation of the aiming angle.

30 Figs. 5 and 6 show a cock whose axis is vertically disposed. Two disks 26 and 27, fitting exactly upon one another, comprise recesses so disposed that the rotation of the disk 24 relatively to the disk 27 will allow of obtaining coincidence between said recesses or on the contrary of closing them off. The disk 27 is screwed into the wall of the cock, whilst the disk 27 is on the contrary free to rotate.

35 The axle of the said cock traverses the two disks with easy friction in such manner as to be vertically slideable such as is made necessary by the flattening of the upper packing member, but while its surface is cylindrical adjacent the stationary disk 27, it has one or more flat parts or grooves 40 co-operating with flat parts or studs on the disk 26, to ensure the entraining of the latter in its rotation.

45 Figs. 7 and 8 show modifications of the cannon in accordance with the invention; in these modifications the projectile carries its own cannon charge, so that the chamber 30 situated rearwardly of the partitions serves as a combustion chamber for the powder contained in the powder chamber 31 of the projectile. These two chambers communicate through an orifice 32 formed in the projection 33 of the projectile. The combustion chamber is closed by an obturating breech piece with movable head, for ex-

ample, which need only be opened for cleaning the cannon.

50 The movable head 34 is provided with a striker 35 against which abuts the striker rod 36 contained in the powder chamber of the projectile, at the time when the projectile attains the end of its trajectory. The firing is thus automatically effected at the end of the loading.

55 The striker rod 36, which is held in the known manner by a safety pin which is adapted to be sheared or bent by the shock of the striker, is guided at a point adjacent the orifice 32, and it ends in a head 37 disposed in the fuse-carrying tube.

60 It is observed that the discharge of gas, in the first place through the discharge conduit when the cork is open, and then within the bore, takes place as in the preceding case, but with the difference that only a part of the gas entering the bore comes from the combustion chamber by traversing the tuyère, while another part of the gas comes directly from the powder chamber of the projectile, but this will not substantially 85 change the conditions of functioning of the tuyère.

65 Fig. 7 shows a projectile provided with studs for use with a rifled cannon, whilst Fig. 8 represents a projectile provided with 90 stabilizing wings 38 in a cannon of the smooth bore type.

70 This latter modification affords the greatest rapidity in firing.

Having thus described my apparatus, 100 what I claim as new therein, and my own invention, is:—

1. In a cannon, a powder chamber arranged at the rear part thereof, a bore for the travel of the projectile, a partition between the said chamber and the said bore, a tuyère arranged in the said partition and connecting the said chamber and the said bore, a projection at the rear of the projectile which may be engaged in the said tuyère, an outlet conduit formed in the said partition and opening into the wall of the tuyère and means for regulating the output of the said conduit.

110 2. In a cannon, a powder chamber arranged at the rear part thereof, a bore for the travel of the projectile, a partition between the said chamber and the said bore, a tuyère arranged in the said partition and connecting the said chamber and the said bore, a projection at the rear of the projectile which may be engaged in the said tuyère, an outlet conduit formed in the said partition and opening into the wall of the tuyère in front of the projection of the projectile and means for regulating the output of the said conduit.

120 3. In a cannon, a powder chamber arranged at the rear part thereof, a bore for the travel of the projectile, a partition be-

- tween the said chamber and the said bore, a tuyère arranged in the said partition and connecting the said chamber and the said bore, a projection at the rear of the projectile which may be engaged in the said tuyère, an outlet conduit formed in the said partition and opening into the wall of the tuyère and a cock disposed in the said outlet conduit.
10. 4. In a cannon, a powder chamber arranged at the rear part thereof, a bore for the travel of the projectile, a partition between the said chamber and the said bore, a tuyère arranged in the said partition and connecting the said chamber and the said bore, a projection at the rear of the projectile which may be engaged in the said tuyère, an outlet conduit formed in the said partition and opening into the wall of the tuyère, a cock disposed in the said outlet conduit, means for aiming the cannon for elevation and connecting organs between the said means and the said cock.
15. 5. In a cannon, a powder chamber arranged at the rear part thereof, a bore for the travel of the projectile, a partition between the said chamber and the said bore, a tuyère arranged in the said partition and connecting the said chamber and the said bore, a projection at the rear of the projectile which may be engaged in the said tuyère, a powder chamber in the rear part of the said projectile, a channel connecting the said chamber with the powder chamber of the cannon, an outlet conduit formed in the said partition and opening into the wall of the tuyère and means for regulating the output of the said conduit.
20. 6. In a cannon, a powder chamber arranged at the rear part thereof, a bore for the travel of the projectile, a partition between the said chamber and the said bore, a tuyère arranged in the said partition and connecting the said chamber and the said bore, a projection at the rear of the projectile which may be engaged in the said tuyère, an outlet conduit formed in the said partition and opening into the wall of the tuyère and means for regulating the output of the said conduit.

connecting the said chamber and the said bore, a projection at the rear of the projectile which may be engaged in the said tuyère, an outlet conduit formed in the said partition and opening into the wall of the tuyère, a cock disposed in the said outlet conduit means for aiming the cannon for elevation, connecting organs between the said means and the said cock and means for controlling by hand the said cock.

6. In a cannon, a powder chamber arranged at the rear part thereof, a bore for the travel of the projectile, a partition between the said chamber and the said bore, a tuyère arranged in the said partition and connecting the said chamber and the said bore, a projection at the rear of the projectile which may be engaged in the said tuyère, a powder chamber in the rear part of the said projectile, a channel connecting the said chamber with the powder chamber of the cannon, an outlet conduit formed in the said partition and opening into the wall of the tuyère and means for regulating the output of the said conduit.

In testimony whereof I have hereunto affixed my signature.

EMILE RIMAILHO.
